(57) **CLAIM**

The ornamental design for a camera housing, as shown and described.

DESCRIPTION

FIG. 1 is a rear perspective view of a camera housing showing my new design;

FIG. 2 is a front perspective view of the camera housing;

FIG. 3 is a front view of the camera housing;

FIG. 4 is a rear view of the camera housing;

FIG. 5 is a left side view of the camera housing;

FIG. 6 is a right side view of the camera housing;

FIG. 7 is a top view of the camera housing; and,

FIG. 8 is a bottom view of the camera housing.

1 Claim, 8 Drawing Sheets**FIG. 1**

FIG. 2

FIG. 3

FIG. 4

FIG. 5

FIG. 6

FIG. 7

FIG. 8
